(57) **CLAIM**

The ornamental design for a floor car jack foot pedal as shown and described.

DESCRIPTION

FIG. 1 is a top, front, left perspective view of a floor car jack foot pedal showing my new design;

FIG. 2 is a top, front, right perspective view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof;

FIG. 8 is a front elevational view thereof;

FIG. 9 is a bottom, front, left perspective view thereof;

FIG. 10 is a bottom, rear, left perspective view thereof;

FIG. 11 is a top, rear, right perspective view thereof;

FIG. 12 is a top, rear, left perspective view thereof;

FIG. 13 is a bottom, front, right perspective view thereof; and,

FIG. 14 is a bottom, rear, right perspective view thereof.

The broken lines in the drawings depict portions of the floor car jack foot pedal that form no part of the claimed design.
